(57) **CLAIM**

The ornamental design for an immersion bath for ultrasound-guided surgery as shown and described.

DESCRIPTION

The patent or application file contains at least one drawing executed in color. Copies of this patent or patent application publication with color drawing(s) will be provided by the Office upon request and payment of the necessary fee.

1. Immersion bath for ultrasound-guided surgery

1.1 : Perspective

1.2 : Perspective

1.3 : Top

1.4 : Bottom

1.5 : Front

1.6 : Back

1.7 : Left

1.8 : Cross sectional

Reproductions 1.1 to 1.8 show the design of an immersion bath for ultrasound-guided surgery; reproduction 1.8 is a cross-sectional view of the immersion bath, as viewed from the side, taken longitudinally along a vertical cross-sectional plane intersecting the immersion bath along a longitudinal midline; the “SPIRECUT” marking highlighted in green color in reproductions 1.1 and 1.3 is purely illustrative and does not form part of the claimed design.
